DESIGN FOR AN APPLIQUE EMBLEM OR SIMILAR ARTICLE FOR WEARING APPAREL

Charles Emmey, New York, N. Y.

Application December 30, 1937, Serial No. 73,981

Term of patent 7 years

To all whom it may concern:

Be it known that I, Charles Emmey, a citizen of the United States, residing in the city of New York and county of New York, State of New York, have invented a new, original, and ornamental Design for an Applique Emblem or Similar Article for Wearing Apparel, of which the following is a specification, reference being had to the accompanying drawing, forming part thereof.

The figure in the accompanying drawing is a plan view of an applique emblem or similar article for wearing apparel. Said design as shown is of no appreciable thickness.

The lining of the lip portion and cigarette portion as shown on the drawing indicates color contrast.

I claim:

The ornamental design for an applique emblem or similar article for wearing apparel, substantially as shown and described.

CHAS. EMMEY,
